UNITED STATES PATENT OFFICE

ENOCH OHNSTRAND, OF KENMORE, NEW YORK, ASSIGNOR, BY MESNE ASSIGNMENTS, TO
REMINGTON RAND INC., OF NEW YORK, N. Y., A CORPORATION OF DELAWARE

BOOKSTACK

Application filed April 19, 1927. Serial No. 184,924.

This invention relates to book stacks, and has reference more particularly to book stacks formed of sheet metal.

An object of the invention is to provide sheet metal book stacks which may be shipped to a customer knock-down and then assembled by the customer easily and quickly.

Another object of the invention is to provide a construction for a sheet metal book stack which may be manufactured cheaply and which will be very strong and durable in use.

A further object of the invention is to provide a construction for sheet metal book stacks in which the various members are provided with interlocking tongues and apertures, the ends of the book stack having locking lugs which prevent accidental disassembly of the structure after it has once been assembled.

A still further object of the invention is to provide a construction for sheet metal book stacks in which a shelf is provided with a book end adapted to slidily engage one edge of the shelf and to be rigid in construction.

Reference is to be had to the accompanying drawings forming a part of the specification, in which

Fig. 1 is a perspective view of my improved book stack,

Fig. 2 is a sectional elevation through the book stack taken on the line 2—2 of Fig. 1,

Fig. 3 is a longitudinal sectional view through the book stack on the line 3—3 of Fig. 2,

Fig. 4 is a fragmentary perspective view on one end of the improved book shelf,

Fig. 5 is an end view of the interlocking hook on a shelf end,

Fig. 6 is an end view of an interlocking tongue on the shelf end,

Fig. 7 is a sectional view through the book

stack on line 7—7 of Fig. 1 showing the book rest, and

Fig. 8 is a fragmentary view on a large scale similar to Fig. 7, showing the book end or rest being attached to the edge of a shelf. 50

Referring to the drawings by numerals, 10 indicates vertical standards which are preferably made of sheet metal and are in the form of a square tube. A series of slots or apertures 11 is formed in the front face 12 55 of each tube, said apertures being adapted to receive hooks 13 and lugs 14 formed on shelf ends 15.

The hook 13 is formed near the upper edge of each shelf end 15, said hook being adapted 60 to engage the metal section 16 between adjoining apertures 11. The tubes 12 are preferably made of fairly heavy gauge metal so that they will be rigid and strong when supporting the weight of a large number of 65

books. It is necessary to make the slots 11 fairly wide in punching heavy gauge metal so that undue breakage of the punches will be avoided. The slots 11 are therefore wider than the thickness of the metal forming the 70 shelf ends 15, and in order to prevent undue play or movement of the hooks 13 in said slots 11, a pressed bead 17 is formed in each hook 13. This bead 17 also greatly stiffens and strengthens the hook 13, since said bead 75

extends the full length of the hook and into the body of the shelf end 15. The lugs 14 are also provided with a bulge or bead 18 which flares outwardly from the inward end of said lug, said bead 18 being also adapted 80 to nearly fill the space in each slot 11. In applying the shelf end 15 to the standard 10, the hook 13 is first inserted in the desired slot, and the lower end of the shelf end 15 is then swung downwardly until the lug 14 85 engages its corresponding slot. It is thus seen that the hook 13 prevents outward movement of the shelf end 15 away from the standard 10, and the lug 14 prevents side play of the lower end of shelf end 15. 90

Each shelf 19 is preferably formed of sheet metal and along each edge is formed a downwardly extending flange 20, on the lower edge of which is formed an inwardly extending flange 21 while an upwardly extending flange 22 is formed along the inner edge of flange 21. It is thus seen that the metal shelves 19 are greatly stiffened by the strengthening flanges formed along each edge. In order to connect the ends of each shelf 19 to the lower edge of shelf ends 15, a downwardly extending flange 23 is formed on each end of shelves 19, and a plurality of slots or apertures 24 are formed in each flange 23. A series of 15 tongues 25 are struck out near the lower edge of shelf end 15, said tongues lying in a plane inside the plane of shelf end 15 and being adapted to enter corresponding slots 24 in flanges 23. The shelves 19 are attached to 20 shelf ends 15 by first inserting the tongues 25 in slots 24 and then forcing the shelf 19 rearwardly relative to shelf end 15 so that each tongue resiliently grips the metal section 26 between adjoining slots 24. When 25 the shelf 19 has been moved to its rearmost position relative to shelf end 15, an offset bead 27 formed in each shelf end 15 has a square shoulder 28 which drops into and engages the inner edge of rear flange 20 so that 30 subsequent accidental disassembly or movement of the shelf 19 relative to shelf end 15 is prevented.

It is desirable to provide a book rest or book end 29 for the shelves 19 which will support a few books B, less than the number of books required to fill the space between shelf ends 15. This book end 29 is also preferably formed of sheet metal and comprises a body portion 30 having a laterally extending vertical flange 31 formed on its front edge, the lower edge of said flange 31 being adapted, preferably but not necessarily, to engage a laterally extending flange 32 formed along the bottom edge of body portion 30. It is thus seen that the engagement of the lower edge of flange 31 with flange 32 stiffens the structure of the book end and prevents the body portion 30 from being distorted out of a vertical plane by the weight of heavy books. 45 For the purpose of detachably securing the book end 29 to a shelf 19, a downwardly extending flange 33 is formed along the front edge of flange 32, and an inwardly extending flange 34 is formed along the bottom edge of flange 33. An offset flange 35 is connected to the flange 34 and terminates in an upwardly extending flange 36 formed on the inner edge of flange 35. The purpose of the offset between flanges 34 and 35 is that the flange 35 55 first permits the easy assembly of the book end 29 to a shelf 19 as seen in Fig. 8 and when the book rest 29 is moved to vertical position with flange 32 abutting the shelf 19, the flange 34 will make a tight fit with the edge of shelf 60 19 and prevent undue play of the book end 29.

Each standard 10 is preferably provided with two vertical series of slots 11 so that each standard 10 will support a pair of shelf ends 15 with the inner faces of the adjoining book ends spaced closely together in parallel 70 relation. It should be understood that the upper ends of tubes 12 will be secured to the wall of a room which contains the book stacks and that the weight of the books will be supported by shelves 19 indirectly by the cantilever action of shelf ends 15 on standards 75 10.

I would state in conclusion that while the illustrated example constitutes a preferred embodiment of my invention, I do not limit myself precisely to the details herein described, since manifestly the same can be considerably varied without departing from the spirit of the invention as defined in the appended claims.

Having thus described my invention, I claim as new and desire to secure by Letters Patent,

1. In a book stack, a plurality of standards adapted to be secured in substantially vertical position, a plurality of shelf ends secured along one edge to said standards so that said shelf ends lie in a substantially vertical plane, a shelf extending between a pair of adjacent shelf ends, a downwardly extending flange formed at each end of said shelf, said flange being provided with a series of apertures, and a series of offset tongues formed along the bottom edge of each shelf end, said tongues being adapted to enter said apertures and lock said shelf to said shelf ends, said tongues forming the means for securing said shelf to said shelf ends.

2. In a book stack, a plurality of standards adapted to be secured in substantially vertical position, a plurality of shelf ends secured along one edge to said standards so that said shelf ends lie in a substantially vertical plane, a shelf extending between a pair of adjacent shelf ends, a downwardly extending flange formed at each end of said shelf, said flange being provided with a series of apertures, a series of offset tongues formed along the bottom edge of each shelf end, said tongues being adapted to enter said apertures and lock said shelf to said shelf ends, and a bead formed on each shelf end adapted to engage said shelf for locking the shelf to the shelf end and preventing the accidental disassembly thereof.

3. In a book stack, a pair of shelf ends adapted to be supported adjacent one edge so that said shelf ends lie in a substantially vertical plane, a shelf extending between said pair of shelf ends, interlocking tongues and apertures associated with said shelf ends and shelf, and a bead associated with said shelf end adapted to prevent the accidental disassembly of the tongues from said apertures.

4. In a book stack, a pair of shelf ends

adapted to be supported adjacent one edge so that said shelf ends lie in a substantially vertical plane, a shelf extending between said pair of shelf ends, said shelf having end flanges formed with a series of openings, said shelf ends having a series of horizontally projecting tongues thereon in aligned relation adjacent the lower edges, said tongues having interlocking connection with said end flanges
5 and extending through the openings therein.
